JOHN MILHOLLAND, OF NEW CONCORD, OHIO.

Letters Patent No. 78,114, dated May 19, 1868.

IMPROVEMENT IN HORSE HAY-FORKS.

The Schedule referred to in these Letters Patent and making part of the same.

TO ALL WHOM IT MAY CONCERN:

Be it known that I, JOHN MILHOLLAND, of New Concord, in the county of Muskingum, and State of Ohio, have invented a new and improved Horse Hay-Fork; and I do hereby declare that the following is a full, clear, and exact description thereof, which will enable others skilled in the art to make and use the same, reference being had to the accompanying drawings, forming part of this specification.

This invention relates to an improved horse hay-fork, and consists of an adjustment of the trip-cord by means of a trigger and of the handle, whereby the handle is protected by the side of the eye when the fork is loaded, and the point kept straight when the fork is to be returned.

In the accompanying drawings—

Figure 1 is a side view of my improved fork when loaded and about to carry its load.

Figure 2 is a front view, the red lines showing the position of the fork when depositing its load or being returned.

Similar letters of reference indicate like parts.

A is the shaft of the fork, to which the prong α is hinged, as shown in the drawing, fig. 1. B is the sliding rod fitting into the fork, and secured by the pivot or pin b.

The handle C falls (when the fork is loaded) below the eye D, which serves to protect it from a blow, which might throw open the fork and discharge the load. The handle C is connected with the sliding bar B by the arms E E, which are free to turn on the pivots or pins e e', by which they are secured to the handle and sliding bar. The handle C terminates in two arms, which embrace the stud e, (firmly attached to the shaft A,) and are secured to the stud e by the pin e', on which they move as a pivot.

F f is a trigger, in form of a bent lever, having its fulcrum on the pivot or pin e. The trip-cord X is attached to the end of the arm F of the trigger, and passes over the stud e through a hole in the shaft A.

To work the fork, place it in the position a', fig. 2, press it into the hay, and lower the handle, whereby the fork is drawn up into the position a. The load is raised in place, the trigger pulled upon by the cord X, thereby pressing the arm f against the shaft A, and slightly raising the handle C, when the weight of the load forces the fork open, and the load is discharged, and the fork returned in the position a', avoiding all risk of its catching in the hay and dragging it from its place of deposit, as often happens with the ordinary forks now in use.

What I claim as new, and desire to secure by Letters Patent, is—

The construction and arrangement of the handle C, connected with the sliding bar B by the arm E turning on the pivots e e', the lower ends of said handle pivoted to the stud e upon the bar A, the bent trigger F f pivoted upon the pin e of the bars E and handle C, all operating as described, for the purpose specified.

JOHN MILHOLLAND.
